UNITED STATES PATENT OFFICE.

CHARLES C. BLAKE, OF BROOKLINE, MASSACHUSETTS.

INSOLE-ROUNDING MACHINE.

Application filed August 8, 1916. Serial No. 113,722.

To all whom it may concern:

Be it known that I, CHARLES C. BLAKE, a citizen of the United States, residing at Brookline, in the county of Norfolk and

5 State of Massachusetts, have invented a new and useful Improvement in Insole-Rounding Machines, of which the following is a specification.

The present invention relates to machines 10 for use in the manufacture of lasts and shoes, and more particularly to sole rounding machines.

The principal object of the present invention is to provide a novel construction 15 and arrangement of devices for operating upon and for supporting the work whereby the rounding operation is performed in an accurate and reliable manner.

To the accomplishment of this object, and 20 such others as will hereinafter appear, the features of the invention relate to certain devices, combinations and arrangements of parts hereinafter described and then set forth broadly and in detail in the appended 25 claims which possess advantages readily apparent to those skilled in the art.

The various features of the present invention will be best understood from an inspection of the accompanying drawings 30 illustrating the preferred embodiment of the invention as constructed for rounding an insole secured to a last bottom, in which,

Figure 1 is a front elevation of the insole rounding machine;

35 Fig. 2 is a detail in front elevation of the tools for rounding the insole;

Fig. 3 is a right side sectional elevation on the line 3—3, Fig. 2;

Fig. 4 is a detail in right side elevation 40 of the insole rounding tools;

Fig. 5 is a plan of the platen or work supporting table;

Fig. 6 is a right side sectional elevation on the line 6—6, Fig. 5;

45 Fig. 7 is a front sectional elevation on the line 7—7, Fig. 5;

Fig. 8 is a sectional plan on a plane cutting the clutch for the shifting mechanism;

Fig. 9 is a right side sectional elevation 50 on a plane cutting the clutch for the shifting mechanism;

Fig. 10 is a detail in sectional plan of the shifting bracket;

Fig. 11 is a detail in right side elevation of the starting and stopping mechanism for 55 driving the leader and the shifting mechanism;

Fig. 12 is a diagrammatic plan illustrating the relation between the edge of the rounded insole and the guiding flange on 60 the leader;

Fig. 13 is an elevation of the last having a rounded insole attached thereto;

Fig. 14 is a detail in elevation of the leader; and

Fig. 15 is a sectional detail on the line 15—15, Fig. 14.

In the illustrated embodiment of the invention a roughly died-out insole 1 (Fig. 1) is secured to a last 2 which is jacked upon 70 a work support 3 of the saddle and spindle type. The work support 3 is provided with runners 4 which slide on a platen or table 5 secured upon the upper end of a post 6 which is mounted for vertical movement in 75 bearings 7 formed in a bracket 8. The top of the bracket 8 is provided with four slots 9 (Fig. 10) which loosely embrace four bolts 10 on a column 11 in order that the bracket 8 may be guided to slide in a fixed 80 path on the column.

In order to feed the work support 3 over the table 5 and thus transfer the point of operation of the operating means around the insole the work support 3 is mounted on a leader 12 (Figs. 1 and 15) provided with a guiding flange 13. As shown in Fig. 12 the projections of the edge of the bottom of the last at the sides thereof upon the plane of the leader coincide with the inside face of the guiding flange. At the toe the projections of the edge of the last bottom upon the plane of the leader fall within the guiding flange. This variation at the toe of the leader is for the accommodation of the toe-box which in a subsequent operation will be applied to the toe-end of the insole. When the upper having the toe-box within it is lasted to the edge face of the insole in accordance with the method of lasting 100 practised by me the projections of the free edge of the upper upon the plane of the leader will coincide with the inside face of the guiding flange throughout its length. Stated in another way, the projections upon 105 the plane of the leader of the outside edge

of the toe-box secured in position on the toe of the insole will coincide with the guiding flange at the toe of the leader.

The leader is actuated to transfer the point of operation of the tool around the insole by a pinion 14 (Fig. 7) which engages rack teeth 15 (Figs. 12 and 14) formed on the exterior face of the guiding flange 13. The pinion 14 is secured to the upper end of a short shaft 16 which carries at its lower end a bevel gear 17 engaged with a similar gear 18. The bevel gear 18 is connected by a universal joint 19 to a short shaft 20 (Fig. 9) which is connected by a universal joint 21 to a shaft 22 journaled in the column 11. The shaft 22 carries a worm wheel 23 which meshes with a worm 24 on a shaft 25 also journaled in the column 11. The shaft 25 (Fig. 1) is driven from a short shaft 26, journaled in a bracket 27 on the base of the machine, by a belt 28 which passes over pulleys on the shafts 25 and 26, respectively.

In order to correct the relative position of the operating means and the insole during the transfer of the point of operation of the operating means around the insole to maintain the edge of the insole in proximity to the operating means in the line of feed the guiding flange 13 on the leader is engaged by a cylindrical pin 29 (Fig. 5) arranged to engage inside the flange and by guide rolls 30 and 31 arranged to engage outside the flange. These guiding devices are mounted on supports secured to the bottom of the table 5 and are positioned above the table 5 through an opening 32 formed therein. The support for the pin 29 is a lever 33 one end of which pivots at 34 and the other end of which slides in ways 35 secured to the bottom of the table 5. The lever 33 is swung to engage the guide pin 29 with the guiding flange 13 by a toggle 36 the links of which are pivoted to the bottom of the table 5 and to the lever 33, respectively. When the toggle is made the pin 29 is locked in engagement with the inside face of the guiding flange. The toggle 36 is made or broken by a handle 37 forming an extension of one of the links of the toggle.

In order to hold the leader down upon the work table the exterior face of the guiding flange 13 is bevelled as shown at 38 (Fig. 15). This bevelled surface is engaged by the frusto-conical guide rolls 30 and 31. With this construction the guides 29, 30 and 31 have a three-point contact with the guiding flange and thus act to swing the work laterally during its feed to correct the relative position of the operating means and the insole and thereby maintain the edge of the insole adjacent the operating point in the line of feed. To enable the rolls 30 and 31 to engage the flange at all times without

binding as they traverse the reverse curves of the flange at the shank and around the toe the guide rolls 30 and 31 are journaled on the free ends of links 39 and 40, respectively, the rear ends of which are pivoted to a lever 41 pivoted at 42 to the bottom of the table 5. The links 39 and 40 are also pivoted to links 43 and 44 pivoted to the bottom of the table 5. The guide rolls 30 and 31 are thus supported for movement transversely of the feed of the leader exactly as if they were supported on a slide but without the frictional resistance incident to the use of a slide. The rolls 30 and 31 are actuated in a direction to press them against the exterior face of the guiding flange 13 by means of a spring 45 (Fig. 5). At its free end the lever 41 is pivoted to a block 46 which loosely receives a rod 47 pivoted at 48 beneath the table 5. The spring 45 is coiled around the rod 47 and is interposed between the block 46 and a shoulder 49 on the rod.

With this construction the spring 45 normally holds the guide rolls 30 and 31 in the inoperative position shown in Fig. 5. When the guiding flange 13 on the leader is interposed between the inside and outside guides and the handle 37 is actuated in a direction to lock the inside guide 29 against the flange, the outside rolls are pushed forward thus placing the spring 45 under compression. The spring 45 yields during the feed of the leader so that it exerts its maximum and minimum pressures when the rolls 30 and 31 are being transferred around the shank and toe of the leader, respectively. The lever 41, however, inversely transmits the pressure of the spring so that the rolls 30 and 31 are held with a greater pressure against the toe of the leader than they are held against the shank of the leader.

The tool for trimming the roughly die-cut insole to the edge of the last bottom consists of a knife 50 (Figs. 1 and 2) which co-operates with an anvil or foot 51 mounted on a cradle 52. The knife 50 is formed on a block 53 which is mounted on one end of a lever 54 pivoted on a stud 55 carried by the cradle 52. The knife block 53 may be adjusted in the lever 54 by a bolt 56 and then held in adjusted position by a set-screw 57.

The anvil 51 which extends between the insole and the last bottom controls the height of the work. To this end a coiled spring 58 (Fig. 1) is connected at one end to the column 11 and at its other end to a treadle 59 pivoted on the machine base. Intermediate its ends the treadle 59 is connected to the post 6 by a link 60. Depression of the treadle 59 lowers the work table 5 to permit the insertion and removal of the work. When the treadle is released and the anvil 51 positioned between the insole and

the last bottom the work automatically rises and falls under the influence of the anvil 51 and the spring 58 to maintain the insole at the operating point in the same plane notwithstanding the various slopes on the last bottom. The post 6 is guided in its vertical movement by a plurality of rolls 61, on the post, which work in slots 62 formed in the bearings 7.

10 The insole at the operating point is held down upon the anvil 51 by a pressure roll or foot 63 (Figs. 2 and 4) which is journaled on a stud 64. The stud 64 is carried by the lower end of a slide 65 mounted to slide in the cradle 52. The roll 63 is pressed towards the insole by a spring 66 coiled around a rod on the slide 65 and interposed between an arm 67 on the cradle 52 and the top of the slide.

20 In order to vibrate the knife 50 the lever 54 is provided with a cylindrical pin 68 upon which a block 69, provided with trunnions 70 (Figs. 2 and 3), is loosely held by a cotter pin 71. The trunnions 70 support 25 a split yoke 72 (Fig. 3) which is hung on trunnions 73 formed on an eccentric strap 74 which embraces an eccentric 75. The eccentric 75 is secured to a shaft 76 which is supported by bearings 77 formed in a head 30 78 secured to the column 11. The shaft 76 is the armature shaft of an electric motor 79 secured to the cradle 52 and rotates on an axis passing through the point of operation of the knife.

35 During the transfer of the point of operation of the knife 50 around the insole it is desirable that the cradle 52 tip automatically to maintain the knife 50 substantially normal to the insole at the point of operation. To this end a series of balls 80 (Fig. 3) are interposed between a ball race, one member of which is secured to the bearing 77 and the other member of which is secured to the shaft 76. Both of the bearings 77 are 40 provided with ball races so that the shaft 76 is supported in a floating manner by two sets of the balls 80. With this construction the cradle 52 floats on an axis passing through the point of operation of the knife 50 and is tipped automatically during the rounding operation by the combined action of the feet 51 and 63 which adapt themselves to the varying slopes on the last bottom. The knife is thus maintained normal to the 45 insole at the operating point.

If a belt or gear wheel were mounted on the shaft 76 and driven from some external source of power through a belt or gear train the cradle would become unbalanced and the 50 feet 51 and 63 would be held in a fixed position unresponsive to the varying slopes on the last bottom. By directly applying the power to the shaft 76 through the armature of an electric motor the balance of the cradle 55 is preserved and its sensitive response to the

positions assumed by the feet under the influence of the work is ensured.

The knife 50 vibrates in a plane intersecting the edge of the last bottom at the sides thereof. In order to maintain the 70 plane of the knife intersecting the edge of the last bottom during its transfer around the toe of the insole notwithstanding the toe-box variation hereinbefore referred to, the bracket 8 is moved on the column 11 to shift 75 the insole supported from the bracket transversely of the feed. The insole is shifted twice during the rounding operation first to remove the tool from the path determined by the leader and then to return the tool to said 80 path. The knife is thus caused to traverse a detour at the toe of the insole coterminous with the path determined by the leader.

The bracket 8 is shifted by an eccentric 81 (Figs. 8 and 9) on a vertical shaft 82 85 journaled in a sleeve 83 which is mounted for rotation in bearings 84. The eccentric 81 has a strap-and-link connection 85 with a bridge 86 on the bracket 8. The shaft 82, normally inoperative, is driven at the proper 90 intervals through a clutch, one member of which consists of a disk 87 on the shaft, and the other member of which consists of a clutch body 88 surrounding the disk 87 and carried by the sleeve 83. A cylinder- 95 carrying disk 89 is loosely mounted on a collar 90 carried by the shaft 82, and this disk is provided with a laterally-extending flange which lies between the inner surface of the clutch member 88 and the disk 87. 100 The disk 87 is provided with a series of recesses in which the clutch cylinders 91 are carried. The disk 87 is provided with a series of wedging surfaces 92 for cooperating with the cylinders in connecting and 105 disconnecting the clutch members. The cylinder-carrying disk 89 and collar 90 are connected by a spring 93 which tends to rotate the cylinder-carrying disk in a direction to cause the cylinders to wedge between the 110 surfaces 92 and the inner surface of the clutch member 88 and bind the clutch members together. When the clutch members are engaged in the manner described the shaft 82 is driven through a bevel gear 94, 115 on the sleeve 83, which is engaged by a bevel gear 95 on the shaft 22.

The clutch is normally held out of action by means of a controlling stop in the form of a modified bell crank lever 96 (Fig. 8) 120 one end of which normally projects into position to be engaged by a radially projecting lug 97 on the cylinder-carrying disk 89 and prevents rotation of the disk. When the bell crank lever 96 is withdrawn, the 125 spring 93 acts to immediately move the clutch cylinders 91 into position where they are wedged between the surfaces 92 and inner surface of the clutch body 88, and securely unite the parts of the clutch so that 130

motion is imparted to the shaft 82 through the sleeve 83 and connected gearing until a second lug 98 on the ball-carrying disk is engaged by the bell crank lever 96 when the 5 shaft 82 has made one-half a revolution.

The withdrawal of the bell crank lever 96 and the engagement of the clutch which drives the shifting mechanism for the bracket 8 is effected twice during the operation of the rounding knife 50 around the insole by the action of controlling devices 10 on the leader, and the bell crank lever 96 is automatically returned into position to disengage the clutch when the clutch has made 15 one-half a revolution. In the construction shown the bell crank lever 96 is actuated in a direction to withdraw it from the lug 97 by a coiled spring 99 connected at its ends to the column 11 and bell crank lever, respectively.

The bell crank lever 96 is held in lug-engaging position against the tension of the spring 99 by a finger 100 (Figs. 6 and 7) arranged in the path of travel of the bottom 25 of the guiding flange on the leader. To this end the finger 100 is loosely mounted on the lever 33, hereinbefore described as the support for the inside guide pin 29, in position to rest on the elongated end 101 of a bell 30 crank lever 102 (Fig. 6) pivoted beneath the table 5. The lower end of the vertical arm of the bell crank lever 102 is provided with a roll 103 which rides in a vertical slot 104 formed in a yoke 105 (Fig. 9) carried 35 by the modified bell crank lever 96 which is pivoted on a bracket 106 (Fig. 8) carried by the column 11.

During the operation of the knife 50 on the sides of the insole the finger 100 is 40 pressed downwardly by engagement with the bottom of the guiding flange 13, and thus maintains the lever 96 engaged with the lug 97 against the tension of the spring 99. When the knife 50 reaches the point A 45 (Fig. 12) the finger 100 rides into a depression 107 (Fig. 14) under the influence of the spring 99 thus freeing the lug 97 and causing the shaft 82 to be driven through the clutch members. The finger 100 is reset by 50 an incline 108 (Fig. 14) on the leader so that the bell crank lever 96 is returned to a position where it may engage the lug 98 and throw the shaft 82 out of operation after it has completed one-half a revolution. The 55 insole maintains the position to which it has been shifted until the finger 100 rides into a second depression 109 on the other side of the leader and the insole 1 is then shifted back to its original position which 60 brings the knife 50 back to the path determined by the leader at the point B. The finger 100 is again reset by the incline 110.

In order to hold the bracket 8 accurately in its "out" and "in" positions the collar 65 90 (Fig. 9) is provided with a pair of lugs

111 and 112 (Fig. 8) which are engaged successively by a spring-pressed dog 113 pivoted on a bridge 114 carried by the column 11. The dog 113 yields to permit the passage of the lugs during the rotation of 70 the shaft 82 and then slips behind one of the lugs when the clutch members are disengaged. The shaft 82 is held by the dog 113 and bell crank lever 96 in a definite angular position thus accurately defining the limits 75 for the shifting movements of the bracket 8.

In order to indicate to the operative the position of the bracket 8 the top of the column carries a pivoted pointer 115 which is normally held by a leaf spring 116 against 80 a mark 117 to show that the bracket 8 is in its "out" position in which position the knife 50 traverses a path determined by the leader. When the bracket 8 is shifted to its "in" position in which position the knife 50 85 traverses the detour the bracket 8 engages a screw 118 on the pointer 115 and swings it against the tension of the spring 116 to the mark "in" on the column 11.

To provide the cylinder-carrying disk 89 90 with sufficient momentum to insure a positive engagement between the bell crank lever 96 and the lugs 97 and 98, the lower end of the shaft 82 is provided with a gear 119 which meshes with a gear 120 loosely 95 mounted on a short vertical stud 121 supported from the bridge 114. Mounted to rotate with the gear 120 is a fly-wheel 122 which provides the cylinder-carrying disk 89 with sufficient momentum to properly engage the lugs 97 and 98 with the bell crank lever 96.

In order to prevent the tripping of the finger 100 when the leader is withdrawn from the machine the link 40 (Fig. 6) is 105 provided with a cam 123 which, as the link 40 moves back to its original position when the guide pin 29 is unlocked from the leader, engages the bell crank lever 102 and prevents it from moving in a direction to release the bell crank lever 96 from the lug 97. A spring 124 coiled around the finger 100, and interposed between the lever 33 and a head 125 on the finger 100 insures the depression of the finger 100 below the surface 115 of the platen when no leader is in the machine. The spring 124 also insures the engagement of the head 125 with the elongated end 101 of the bell crank lever 102 during the making and breaking of the toggle to 120 engage and disengage the guide pin 29 and the leader.

In the machines heretofore used in my system of shoe manufacture it has been necessary for the operative to carefully position 125 the leader against the driving pinion to insure the rolling contact of the teeth on the pitch line. In order to permit the operative to engage the pinion and leader without special care or attention the pinion 14 is yield- 130

ingly mounted so that in the event that the operative positions the faces of the teeth on the leader and pinion in contact the pinion will automatically find its rolling contact 5 position on the pitch line of the leader. To this end the shaft 16 (Fig. 7) is journaled in a sleeve 126 which is pivoted on a bracket on the post 6. The sleeve is held against a stop 126^a on the post 6 by a plunger 127 10 loosely carried by the table 5. Coiled around the plunger 127 is a spring 128 which is interposed between the table 5 and a collar 129 on the plunger. The plunger is screw-threaded at one end to receive a nut 130 for limiting the position of the plunger. With this construction the spring 128 will yield when the operative positions the face of a tooth on the leader against a face of a tooth on the pinion. Then when the pinion 20 is rotated to drive the leader the spring 128 presses the pinion into proper driving engagement with the leader. The spring 128 also permits the pinion to automatically adapt itself to any irregularities in the 25 teeth on the leader during the drive thereof.

The shaft 26 (Fig. 11) is driven through a friction clutch from an electric motor 131 secured to the base of the machine. The armature shaft 132 carries a friction disk 30 133 mounted adjacent a friction disk 134 on the shaft 26. As well known to those skilled in the art it is possible to provide a magnetic center for the armature shaft 132. That is, while the shaft 132 is free 35 to move longitudinally under pressure applied to one end of the shaft it must always return to a definite central position upon the release of the shaft from endwise pressure. Accordingly, advantage is taken of 40 this magnetic center to provide a novel starting and stopping mechanism for the machine. To this end the base of the machine is provided with a rock shaft 135 having a vertical arm 136 projecting there- 45 from. The upper end of the arm 136 carries a block 137 arranged opposite the rear end of the shaft 132. To rock the shaft 135 and thus engage the block 137 with the shaft 132 the rock shaft 135 carries a 50 second vertical arm 138 which is connected by a rod 139 with a foot treadle 140 pivoted on the base of the machine. When the foot treadle 140 is depressed the shaft 132 is moved longitudinally thus engaging the 55 disk 133 with the disk 134. When the treadle is released the shaft 132 immediately returns to its magnetic center thus withdrawing the disk 133 from the disk 134. At the same time a spring 141 connected at one end to the rod 139 and at its 60 other end to the column 11 forcibly applies a brake 142 on the treadle lever to the disk 134.

In operating the machine the treadle 59 65 is depressed to lower the table 5. The

leader carrying the last having the roughly die-drawn insole attached thereto is then placed on the table with the guiding flange on the leader interposed between the inside and outside guides. The handle 37 70 (Fig. 5) is then actuated to lock the inside guide against the guiding flange thus clamping the leader between the guides under the influence of the spring 45. This movement of the handle 37 releases the bell 75 crank lever 102 from the cam 123 (Fig. 6) thus causing the spring 99 (Fig. 8) to press the finger 100 against the bottom of the guiding flange on the leader. The insole is now positioned in the machine with the 80 insole adjacent the operating point gripped between the roll 63 and anvil 51 which is inserted between the bottom of the last and the insole at approximately one breast corner. The knife 50 having been thrown into 85 operation and the treadle 140 having been depressed to actuate the pinion 14 the insole is trimmed to the edge of the last bottom until the point A (Fig. 12) is reached. At this point the finger 100 rides into the 90 depression 107 thereby freeing the lug 97 and throwing the shifting mechanism into operation to shift the insole and thus cause the knife 50 to start on its detour (Fig. 12). The finger 100 is immediately reset by the 95 incline 108 so that the bell crank lever may engage the lug 98 upon the completion of a half-revolution of the clutch and throw the shifting mechanism out of operation. The knife 50 continues to cut the insole on a line 100 parallel to the path determined by the toe of the leader until the point B is reached when the finger 100 rides into the depression 109 (Fig. 14) and the shifting mechanism is thrown into operation a second 105 time to return the knife 50 to the path determined by the leader. The finger 100 is again reset to hold the shifting mechanism inoperative in its original position. During the transfer of the point of operation 110 of the cutter around the insole the cutter 50 is tipped automatically about its point of operation to maintain it substantially normal to the insole at the point of operation and the insole rises and falls under the influence of the spring 58 and anvil 51 to maintain the bottom of the last adjacent the operating point substantially in the plane of the anvil. At the completion of the cut the treadle 140 is released to stop 115 120 the drive for the pinion 14 and the treadle 59 is depressed to permit the finished work to be withdrawn from the machine.

While the invention has been illustrated and described in connection with a sole 125 rounding machine it will be apparent to those skilled in the art that the features of the invention may be advantageously employed in performing other operations in the manufacture of shoes and parts thereof 130.

and particularly in the manufacture of lasts for determining the shape of the last bottoms.

It will also be clear to those skilled in this class of machines and with the general objects of the present invention in view, that changes may be made in the details of structure, the described and illustrated embodiment thereof being intended as an exploitation of its underlying essentials the features whereof are definitely stated in their true scope in the claims herewith.

What is claimed as new, is:—

1. An insole rounding machine, having, in combination, an insole rounding knife, a sole support, means for relatively actuating the support and the knife to transfer the point of operation of the knife around the sole, a knife carrier, and a plurality of feet mounted on the carrier arranged to engage the sole and adapt themselves to the curvature thereof and swing the carrier during the transfer of the knife around the sole to maintain the knife substantially normal to the sole, substantially as described.
2. An insole rounding machine, having, in combination, an insole rounding knife, a sole support, means for relatively actuating the support and knife to transfer the point of operation of the knife around the sole, a knife carrier, and a plurality of feet mounted on the carrier arranged to grip the sole and adapt themselves to the curvature thereof and swing the carrier during the transfer of the knife around the sole to maintain the knife substantially normal to the sole, substantially as described.

3. A machine of the class described, having, in combination, an operating tool, a carrier therefor mounted to freely tip about an axis passing through the point of operation of the tool, and a source of power on the carrier balanced to drive the tool without interference with the freedom of tipping of the carrier, substantially as described.

4. A machine of the class described, having, in combination, an operating tool, a carrier therefor mounted to freely tip about an axis passing through the point of operation of the tool, and means for driving the tool without interference with the freedom of tipping of the carrier comprising an electric motor having the axis of its shaft coinciding with the axis about which the carrier tips, substantially as described.

5. A sole rounding machine, having, in combination, a rounding knife, a cradle therefor mounted to freely tip about an axis passing through the point of operation of the knife, and a source of power balanced on the said axis to drive the knife without interference with the freedom of tipping of the cradle, substantially as described.
6. A rounding machine, having, in combi-

nation, a rounding knife, and a driving mechanism therefor comprising a tipping shaft the axis of which passes through the point of operation of the knife, substantially as described.

7. A rounding machine, having, in combination, a rounding knife, a driving mechanism therefor, and a support for the knife and its driving mechanism mounted to tip about an axis substantially coincident with the point of operation of the knife, substantially as described.

8. A rounding machine, having, in combination, a head having bearings thereon, a motor having its shaft mounted to tip in the bearings, a rounding knife, and connections between the knife and the motor shaft for driving the knife, substantially as described.

9. A rounding machine, having, in combination, a head having bearings thereon, a motor having its shaft mounted to tip in the bearings, a carrier secured to the motor, a lever pivoted on the carrier, a rounding knife carried by the lever, and connections between the lever and the motor shaft for oscillating the lever, substantially as described.

10. A rounding machine, having, in combination, a support for a last having a roughly died-out insole attached thereto, an anvil mounted to extend between the last and the insole, a rounding knife co-operating with the anvil to trim the insole to the edge of the last bottom, and a support for the knife and anvil mounted to tip freely about an axis substantially coincident with the point of operation of the knife, substantially as described.

11. A rounding machine, having, in combination, a support for a last having a roughly died-out insole attached thereto, an anvil mounted to extend between the last and the insole, means for maintaining the last engaged with the anvil, a rounding knife co-operating with the anvil to trim the insole to the edge of the last bottom, and mechanism for relatively actuating the support and knife to transfer the point of operation of the knife around the insole, substantially as described.

12. A rounding machine, having, in combination, a support for a last having a roughly died-out insole attached thereto, an anvil mounted to extend between the last and the insole, and a rounding knife co-operating with the anvil to trim the insole to the edge of the last bottom, substantially as described.

13. A machine of the class described, having, in combination, an operating tool, a work support, a leader connected thereto, means for actuating the leader to transfer the point of operation of the tool around the work, means for swinging the leader.

- during a predetermined part of the transfer of the point of operation of the tool around the work about an axis passing substantially through the point of operation of the tool,
- 5 5. mechanism for relatively shifting the tool and leader during another part of the transfer of the point of operation of the tool around the work to remove the point of operation of the tool from proximity to the
- 10 axis about which the leader swings, a driving mechanism for the shifting mechanism, and controlling mechanism acting to throw the driving mechanism into operation, substantially as described.
- 15 14. A machine of the class described, having, in combination, an operating tool, a work support, a leader connected thereto, means for actuating the leader to transfer the point of operation of the tool around the
- 20 work, means for swinging the leader during a predetermined part of the transfer of the point of operation of the tool around the work about an axis passing substantially through the point of operation of the tool,
- 25 mechanism operating first to relatively shift the tool and leader to remove the point of operation of the tool from proximity to the axis about which the leader swings and then to return the point of operation of the tool
- 30 to its normal position, a driving mechanism for the shifting mechanism, and controlling mechanism acting to throw the driving mechanism into operation, substantially as described.
- 35 15. A machine of the class described, having, in combination, an operating tool, a work support, feeding means, means for correcting the relative position of the tool and the support during the feed including
- 40 a leader for determining the path of relative travel of the tool and work support, mechanism for relatively shifting the tool and the work to cause the tool to traverse a detour coterminous with said path, a driving
- 45 mechanism for the shifting mechanism, and controlling mechanism acting to throw the driving mechanism into operation, substantially as described.
- 50 16. A machine of the class described, having, in combination, an operating tool, a work support, feeding means, means for correcting the relative position of the tool and the support during the feed including a leader for determining the relative path of
- 55 travel of the tool and work support, mechanism for relatively shifting the tool and the work to cause the tool to traverse a detour coterminous with said path, a driving mechanism for the shifting mechanism, and con-
- 60 trolling mechanism acting to throw the driving mechanism into and out of operation twice during the traverse of the tool, substantially as described.
- 65 17. A machine of the class described, having, in combination, an operating tool, a work support, feeding means, means for correcting the relative position of the tool and the support during the feed including a leader for determining the relative path of travel of the tool and work support, mechanism for relatively shifting the tool and the work to cause the tool to traverse a detour coterminous with said path, a driving mechanism for the shifting mechanism, a driving clutch therefor, a series of trips on the leader, latching devices for preventing the engagement of the clutch connected to be tripped by the leader, and means acting automatically to reset the latching devices and disengage the clutch, substantially as described.

21. A machine of the class described, having, in combination, an operating tool, a work support, feeding means, means for correcting the relative position of the tool and the support during the feed including a leader for determining the relative path of travel of the tool and work support, mechanism for relatively shifting the tool and the work to cause the tool to traverse a detour coterminous with said path, a driving mechanism for the shifting mechanism, a driving clutch therefor, a spring-operated device and mechanical connections controlling the clutch, means for latching the device in clutch-disengaging position, and mechanism controlled by the leader for operating the latch at intervals, substantially as described. 5 10 15 20 25 30 35 40 45 50 55 60 65
22. A machine of the class described, having, in combination, an operating tool, a work support, feeding means, means for correcting the relative position of the tool and the support during the feed including a leader for determining the path of the tool, mechanism for relatively shifting the tool and the work to cause the tool to traverse a detour coterminous with said path, a driving mechanism for the shifting mechanism, a driving clutch therefor, a spring-operated device and mechanical connections controlling the clutch, means for latching the device in clutch-disengaging position, a series of trips on the leader, and connections between the trips and the latching means, substantially as described. 20 25 30 35 40 45 50 55 60 65
23. A machine of the class described, having, in combination, an operating tool, a work support, feeding means, means for correcting the relative position of the tool and the support during the feed including a leader for determining the path of the tool, mechanism for relatively shifting the tool and the work to cause the tool to traverse a detour coterminous with said path, a driving mechanism for the shifting mechanism, a driving clutch therefor, a stop for controlling the engagement and disengagement of the clutch, a spring for operating the stop to cause the engagement of the clutch, devices for restraining the spring, and controlling mechanism acting to release the spring at intervals during the transfer of the point of operation of the tool around the work, substantially as described. 20 25 30 35 40 45 50 55 60 65
24. A machine of the class described, having, in combination, an operating tool, a work support, feeding means, means for correcting the relative position of the tool and the support during the feed including a leader for determining the path of the tool, mechanism for relatively shifting the tool and the work to cause the tool to traverse a detour coterminous with said path, a driving mechanism for the shifting mechanism, a driving clutch therefor, a stop for controlling the engagement and disengagement of the clutch, a spring for operating the stop to cause the engagement of the clutch, devices for restraining the spring, and controlling mechanism acting to release the spring at intervals during the transfer of the point of operation of the tool around the work, substantially as described. 20 25 30 35 40 45 50 55 60 65
25. A machine of the class described, having, in combination, an operating tool, a work support, a leader carried thereby, feeding means, means for correcting the relative position of the tool and the support during the feed, mechanism for shifting the support to cause the tool to deviate from the path determined by the correcting means, a driving mechanism for the shifting mechanism, and controlling mechanism acting to throw the driving mechanism into operation, substantially as described. 70 75 80 85 90 95
26. A machine of the class described, having, in combination, an operating tool, a work support, a leader carried thereby, feeding means, means for correcting the relative position of the tool and the support during the feed, mechanism for shifting the support to cause the tool to deviate from the path determined by the correcting means, a driving mechanism for the shifting mechanism, tripping devices on the leader for throwing the driving mechanism into operation, and connections between the leader and the driving mechanism, substantially as described. 85 90 95 100
27. A machine of the class described, having, in combination, an operating tool, a work support, a leader carried thereby, feeding means, means for correcting the relative position of the tool and the support during the transfer of the point of operation of the tool around the work, mechanism for shifting the support to cause the tool to deviate from the path determined by the correcting means, a driving mechanism for the shifting mechanism, tripping mechanism acting to throw the driving mechanism into operation, and means acting to reset the tripping mechanism and throw the driving mechanism out of operation, substantially as described. 100 105 110 115 120
28. A machine of the class described, having, in combination, a work support for a piece of work having a toe, a leader carried thereby provided with a guiding flange, a cutter mounted to cut the work at the sides thereof on a line the projections of which upon the plane of the leader coincide with one face of the guiding flange at the sides of the leader, means for relatively actuating the support and cutter to transfer the point of operation of the cutter along the sides and around the toe of the work, mechanism for relatively shifting the support and the cutter during the transfer of the point of operation of the cutter around the toe of the work to cut the work on a line the pro- 120 125 130

jections of which upon the plane of the leader lie within the guiding flange, a driving mechanism for the shifting mechanism, and controlling mechanism acting to throw 5 the driving mechanism into operation, substantially as described.

29. A machine of the class described, having, in combination, a work support for a piece of work having a toe, a leader carried thereby provided with a guiding flange, a cutter mounted to cut the work at the sides thereof on a line the projections of which upon the plane of the leader coincide with one face of the guiding flange 15 at the sides of the leader, means for actuating the leader to transfer the point of operation of the cutter along the sides and around the toe of the work, mechanism for relatively shifting the support and the cutter during the transfer of the point of 20 operation of the cutter around the toe of the work to cut the work on a line the projections of which upon the plane of the leader lie within the guiding flange, a driving mechanism for the shifting mechanism, and controlling mechanism acting to throw 25 the driving mechanism into operation, substantially as described.

30. A machine of the class described, having, in combination, a work support for a piece of work having a toe, a leader carried thereby provided with a guiding flange, a cutter mounted to cut the work at the sides thereof on a line the projections of 35 which upon the plane of the leader coincide with one face of the guiding flange at the sides of the leader, means for actuating the leader to transfer the point of operation of the cutter along the sides and around the toe 40 of the work, mechanism for shifting the support during the transfer of the tool around the toe of the work to cause the cutter to cut the work on a line the projections of which upon the plane of the leader lie 45 within the guiding flange, a driving mechanism for the shifting mechanism, and controlling mechanism acting to throw the driving mechanism into operation, substantially as described.

31. A machine of the class described, having, in combination, an operating tool, a work support, a leader carried thereby, feeding means, means for correcting the relative position of the operating tool and 55 the work during the feed, mechanism for relatively shifting the work support and the tool transversely of the feed including a pattern cam, and devices for intermittently actuating the cam comprising a series 60 of tripping devices carried by the leader, substantially as described.

32. A machine of the class described, having, in combination, an operating tool, a work support, a leader carried thereby, feeding means, means for correcting the 65

relative position of the operating tool and the work during the feed, mechanism for relatively shifting the work support and the tool transversely of the feed, and a series of tripping devices carried by the 70 leader acting successively as the work is fed to throw the shifting mechanism into operation, substantially as described.

33. A machine of the class described, having, in combination, an operating tool, a 75 slide, a work support carried thereby, automatic means for feeding the support on the slide and means for actuating the slide during the feed of the work, substantially as described.

34. A machine of the class described, having, in combination, an operating tool, a work support, a leader carried thereby provided with gear teeth, and a pinion for driving the leader yieldingly mounted to 85 automatically find the pitch line on the leader, substantially as described.

35. A machine of the class described, having, in combination, an operating tool, a work support, a leader carried thereby provided with gear teeth, a pinion for driving the leader, and a spring for holding the pinion engaged with the leader, substantially as described.

36. A machine of the class described, having, in combination, an operating tool, a work support, feeding means, means for correcting the relative position of the tool and the support during the feed including a leader for determining the path of 100 the tool, mechanism for relatively shifting the tool and the work to cause the tool to traverse a detour coterminous with said path, a driving mechanism for the shifting mechanism, means on the leader for holding the driving mechanism inoperative, tripping devices on the leader for throwing the driving mechanism into operation, and connections between the leader and the driving mechanism, substantially as described.

37. A machine of the class described, having, in combination, an operating tool, a work support, feeding means, means for correcting the relative position of the tool and 115 the support during the feed including a leader for determining the path of the tool, mechanism for relatively shifting the tool and the work to cause the tool to traverse a detour coterminous with said path, a driving mechanism for the shifting mechanism, means on the leader for holding the driving mechanism inoperative, tripping devices on the leader for throwing the driving mechanism into operation, connections between 120 the leader and the driving mechanism, and additional means for holding the driving mechanism inoperative when no leader is in the machine, substantially as described.

38. The combination with an operating 130

tool of a work support, a leader secured thereto provided with a guiding flange, means for relatively actuating the tool and the support to transfer the tool around the work, a guide engaging inside the flange and a pair of guides engaging outside the flange co-operating with the flange to swing the support laterally as the tool is transferred around the work, a pivoted arm for the inside guide, and a toggle for locking the inside guide against the flange, substantially as described.

39. The combination with an operating tool of a work support, a leader secured thereto provided with a guiding flange, means for relatively actuating the tool and the support to transfer the tool around the work, a guide engaging inside the flange and a pair of guides engaging outside the flange co-operating with the flange to swing the support laterally as the tool is transferred around the work, and separate links for supporting the outside guides, substantially as described.

40. The combination with an operating tool of a work support, a leader secured thereto provided with a guiding flange, means for relatively actuating the tool and the support to transfer the tool around the work, a guide engaging inside the flange and a pair of guides engaging outside the flange co-operating with the flange to swing the support laterally as the tool is transferred around the work, a pivoted arm for the inside guide, ways for supporting the free end of the pivoted arm, and a toggle for locking the inside guide against the flange, substantially as described.

41. A machine of the class described, having, in combination, an operating tool; a work support; feeding means, means for correcting the relative position of the tool and the support during the feed including a leader provided with a guiding flange for determining the relative path of the tool and work support and a guide engaging inside the flange and a pair of guides engaging outside the flange co-operating with the flange to swing the support laterally as the tool is transferred around the work; mechanism for relatively shifting the tool and the work to cause the tool to traverse a detour coterminous with said path; a driving mechanism for the shifting mechanism; means on the leader for holding the driving mechanism inoperative; tripping devices on the leader for throwing the driving mechanism into operation; connections between the leader and the driving mechanism; support-

ing means for the outside guides; and a cam mounted on the supporting means for holding the driving mechanism inoperative when no leader is in the machine, substantially as described.

42. The combination with an operating tool, of a work support, a table therefor, means for moving the support on the table to transfer the point of operation of the tool around the work, and mechanism for moving the table in and out during the transfer of the point of operation of the tool around the work, substantially as described.

43. The combination with an operating tool, of a work support, a table therefor, means for moving the support on the table to transfer the point of operation of the tool around the work, mechanism for moving the table in and out during the transfer of the point of operation of the tool around the work, and an indicator for indicating the in and out positions of the table, substantially as described.

44. A shoe machine, having, in combination, an operating tool, a sole support, means for relatively actuating the support and the tool to transfer the point of operation of the tool around the sole, a tool carrier, and a plurality of feet mounted on the carrier arranged to engage the sole and adapt themselves to the longitudinal curvature thereof and swing the carrier during the transfer of the tool around the sole to maintain the tool substantially normal to the sole, substantially as described.

45. A shoe machine, having, in combination, an operating tool, a shoe support, means for feeding the shoe support past the tool, a tool carrier mounted to tip about an axis extending across the direction of feed of the shoe support, and a plurality of feet operatively connected to the tool carrier arranged to engage the work on the shoe support and adapt themselves to the curvature thereof and swing the tool during the feed to maintain the tool substantially normal to a face on the work.

46. The combination with an operating tool of a driving mechanism therefor comprising a motor mounted to adjust itself to the position required by the tool.

47. A shoe machine, having, in combination, a horizontal table, a work support freely movable on the table, a vertically movable post for the table, and guiding means for the post comprising a bearing and a roll and slot connection between the post and the bearing.

CHARLES C. BLAKE.
